[57] **CLAIM**

The ornamental design for a combined shipping and display container for cut flowers, as shown and described.

DESCRIPTION

FIG. 1 is a perspective view of a combined shipping and display container showing my new design, seen from an angle showing the left side, front side and top, the right side of the container being a mirror image of the left side;

FIG. 2 is a view similar to FIG. 1 but showing a portion removed for display purposes;

FIG. 3 is a front elevational view in the display condition;

FIG. 4 is a plan view thereof;

FIG. 5 is a side elevational view thereof;

FIG. 6 is a rear elevational view thereof; and

FIG. 7 is a bottom plan view thereof.

The dash lines in FIGS. 1, 2 and 3 represent score lines.
